UNITED STATES PATENT OFFICE

ERNESTINE N. POLE, OF HOT SPRINGS, VIRGINIA

FLOWER HOLDER

Application filed December 29, 1932. Serial No. 649,405.

The present invention relates to new and useful improvements in flower holders and has for some of its objects to provide, in a manner as hereinafter set forth, a device of 5 this character which will be simple in construction, strong, durable, attractive in appearance, and which may be manufactured at low cost.

All of the foregoing and still further objects 10 and advantages of the invention will become apparent from a study of the following specification, taken in connection with the accompanying drawing wherein like characters of reference designate corresponding parts 15 throughout the several views, and wherein:—

Figure 1 is a view in top plan of a flower holder constructed in accordance with the present invention.

Figure 2 is a view in side elevation thereof. 20 Figure 3 is a bottom plan view.

Figure 4 is a detail view in section, taken substantially on the line 4—4 of Figure 3.

Referring now to the drawing in detail, it will be seen that the embodiment of the 25 invention which has been illustrated comprises a plurality of substantially upright, longitudinally curved plates 1 which terminate in points at their upper ends, said plates also being curved in transverse section and 30 having portions of their vertical side portions extending in overlapping relation and secured together by suitable means, such as soldering, riveting or welding, as at 2.

Mounted in the chamber defined by the 35 plates 1 is a pair of substantially similar but comparatively small plates 3 which also overlap each other and are secured together. The pointed upper ends of the plates 3 are secured to intermediate portions of the plates 40 1 by any suitable means, such as soldering or welding, as at 4. As best seen in Figure 3 of the drawing, arms 5 project horizontally from the lower ends of the plates 3 and said arms are secured, at their outer ends, to the 45 lower portions of certain of the plates 1 by suitable means, such as soldering or welding.

Mounted on the outer sides of pairs of plates 1 and bridging the joints connecting said pairs of the plates, are substantially similar plates 6 which are rigidly secured to the

plates 1 by suitable means, such as soldering or welding. The mounting of the plates 6 on the plates 1 is best illustrated in Figure 3 of the drawing. All of the plates 1, 3 and 6 are of suitable ductile material, preferably lead in sheet form, and said plates are preferably shaped to conform to the petals of flowers.

It will thus be seen that the construction and arrangement of the bendable or ductile plates 1, 3 and 6 is such as to provide a plurality of chambers or sockets 7 for the reception of the flower stems. It will further be seen that the flowers will be held or displayed in a highly attractive manner by reason of the shape and arrangement of the plates constituting the holder. As best seen in Figure 2 of the drawing, the bottom of the holder is flat, permitting same to be readily mounted on any suitable support. The plates 1, 3 and 6 have formed therein longitudinal ribs or beads 8 which preferably extend from end to end of said plates. The plates being ductile, may, of course, be easily worked into various shapes.

It is believed that the many advantages of a flower holder constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A flower holder comprising a plurality of substantially upstanding, outwardly curved plates having overlapping marginal portions secured together, a pair of inner plates mounted within the first named plates and secured thereto, the inner plates being substantially similar in shape to the outer plates and being secured together, the inner plates being smaller than the outer plates, and a pair of plates mounted exteriorly on the first named plates and being substantially similar in shape thereto, the third named plates bridging the joints of certain of the first named plates.

2. A flower holder comprising a plurality of substantially upstanding, outwardly curved plates having overlapping marginal portions secured together, a pair of inner plates mounted within the first named plates and secured thereto, the inner plates being substantially similar in shape to the outer plates and being secured together, the inner plates being smaller than the outer plates, and 5 a pair of plates mounted exteriorly on the first named plates and being substantially similar in shape thereto, the third named plates bridging the joints of certain of the first named plates, all of the plates being of ductile 10 metal, said plates, in conjunction with each other, defining chambers for the reception of 15 the flowers.

3. A flower holder comprising a pair of inner plates with lower upright portions of arcuate cross section, having their edges joined together to form an upright tube, and with upper, outwardly extending portions the edges of which are separated by intervening spaces, and a plurality of outer plates with lower upright tube forming portions of arcuate cross section, grouped about and connected with the lower portions of the inner plates, and with upper, outwardly extending free portions.

In testimony whereof I affix my signature.

ERNESTINE N. POLE.
